J. E. SHOPE.

RAIL CHAIR AND FASTENER.

APPLICATION FILED DEC. 7, 1914.

1,154,445.

Patented Sept. 21, 1915.

UNITED STATES PATENT OFFICE.

JAMES E. SHOPE, OF CONNELLSVILLE, PENNSYLVANIA.

RAIL CHAIR AND FASTENER.

1,154,445.

Specification of Letters Patent. Patented Sept. 21, 1915.

Application filed December 7, 1914. Serial No. 875,908.

To all whom it may concern:

Be it known that I, JAMES E. SHOPE, citizen of the United States, residing at Connellsville, in the county of Fayette and State of Pennsylvania, have invented certain new and useful Improvements in Rail Chairs and Fasteners; and I do declare the following to be a full, clear, and exact description of the invention, such as will enable others skilled in the art to which it app pertains to make and use the same.

My invention relates to improvements in rail chairs and fasteners and it has for its object to improve upon United States Patent 588,360 issued to me August 17, 1897.

Among other features, this patent includes a rigid fish plate having means for attachment to the cross ties, said rigid plate contacting with the inner sides of the rails, a movable fish plate contacting with the outer sides thereof, means for forcing the movable plate toward the fixed plate to securely clamp the rails therebetween, and pins projecting from the fixed plate through aligned openings in the rails and in the movable plate.

This construction, although very efficient in climates where the temperature does not suddenly change has been found to be inefficient in other climates, on account of the fact that sudden changes in temperature cause the rails to so suddenly expand or contract, as the case may be, as to cause the pins to be sheared off. With a device constructed as shown in this patent, it is impossible to replace these pins without replacing the entire rigid fish plate.

The object of the invention is, therefore, to provide means for removably securing the pins to one of the fish plates, whereby should one or any number of these pins be broken, they may be quickly and easily replaced.

To the above end, the invention resides in certain novel features of construction and combination herein described and shown in the drawings wherein:

Figure 1 is a top plan view of a device constructed in accordance with my invention; and Figs. 2 and 3 are detail vertical transverse sections as seen on the lines 2—2 and 3—3 of Fig. 1.

In these drawings, forming a part of this application the meeting ends of a pair of rails R are shown, said ends being supported

on the usual cross ties T, two of the latter being here shown. Interposed between the two ties T is a base plate 1 which underlies the bases of the rails and whose outer end is integrally united with a bridge plate 2 which overlies the outer ends of the ties and which is secured thereto by a pair of spikes 3. The center of this bridge plate 2 is provided with an outwardly and upwardly inclining boss 4 for a purpose to appear. Integrally united with the inner end of the base plate 1, is a rigid fish plate 5, said plate being provided with a pair of inwardly projecting attaching plates 6 at its opposite ends, said plates 6 being secured to the ties by any suitable number of spikes 7, two being here shown as passing through each plate.

By reference more particularly to Figs. 2 and 3, it will be seen that the rigid fish plate 5 contacts with the inner sides of the two rails R and that a movable fish plate 8 contacts with the outer sides of these rails, said plate 8 being provided with a downwardly and outwardly inclining arm 9 which projects through an opening 10 in the base plate 1 and which contacts with the outer wall of said opening. With the parts in this position, a bolt 11 is passed through the free end of the arm 9, upwardly through the bridge plate 2 and boss 4 thereon, and is equipped with a clamping nut 12, whereby tightening of the latter will rock the arm 9 in a direction to force the movable fish plate 8 toward the fixed plate 5, thereby securely clamping the rail sections therebetween. On the other hand, removal of the bolt 11 will allow the plate 8 to be removed.

At suitably spaced intervals, the rigid fish plate 5 is provided with tapered openings 13 which extend transversely therethrough, the contracted ends of said openings being located adjacent the inner side of said plate as shown. These openings 13 align with circular openings which are formed through the webs of the rails R and through the movable plate 8. With the parts in this position, pins 14 having tapered inner ends 15 are passed through the aligned openings in the movable fish plate and in the rails, and have their tapered inner ends 15 snugly seated in the openings 13 and projecting inwardly beyond the latter, cotter pins 16 being then passed through these projecting ends, whereby to prevent removal of the pins 14.

- With the parts constructed as above described, should any of the studs or pins 14 be sheared off by expansion or contraction of the rails they may be easily removed by 5 removing the cotter pins 16 and new pins may be substituted therefor. This is evidently a marked improvement over the patent above mentioned. By providing pins of substantially the same size throughout their 10 length, a slight longitudinal movement of the rails and plates on said pins is attainable, thus allowing for expansion and contraction of the parts and also to allow for slight adjustments.
- 15 As clearly shown in Figs. 2 and 3, the sides of the fish plates 5 and 8 which contact with the rails R are provided with longitudinal grooves, this provision being made in order that current conducting bonds may 20 be employed for electrically connecting the meeting ends of the rails.
- Although these changes are simply matters of degree, I have decreased the number of spikes used in securing the device to the 25 ties, but have increased the number of pins, since practically all rails now in use, are provided with six bolt receiving openings, this number of pins being therefore shown.
- From the foregoing description taken in 30 connection with the accompanying drawings it will be seen that a comparatively simple yet highly efficient device is provided for carrying out the objects of the invention.

Copies of this patent may be obtained for five cents each, by addressing the "Commissioner of Patents, Washington, D. C."

I claim.

The combination with the meeting ends of 35 a pair of rails, a rigid fish plate contacting with one side thereof, having means for attachment to a cross tie, said rigid plate having a longitudinal groove in its inner side adjacent said rail, connecting with a series 40 of openings which taper toward the outer side of said rails, a movable fish plate contacting with the outer side of said rails, means for moving said movable plate toward the rigid plate, said movable plate having a 45 longitudinal groove in its inner side adjacent said rail connecting with a series of openings which are of the same size throughout their length, pins tapering to one end for a portion of their length and of the 50 same size throughout the remaining portion, said tapered ends adapted to be inserted in the tapered openings in the rigid fish plate with their uniform portions in the alined openings in the movable plate and in 55 the openings through the track rails, and means in conjunction with the outer ends of said pins for preventing their removal.

In testimony whereof I have hereunto set my hand in presence of two subscribing witnesses.

JAMES E. SHOPE.
